UNITED STATES PATENT OFFICE.

FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

RIVETING-MACHINE.

1,182,594.

Specification of Letters Patent.

Patented May 9, 1916.

Application filed June 15, 1915. Serial No. 34,223.

To all whom it may concern:

Be it known that I, FREDERICK E. STANLEY, a citizen of the United States, residing at Waterbury, in the county of New Haven and State of Connecticut, have invented a certain new and useful Improvement in Riveting-Machines, of which the following is a full, clear, and exact description.

The immediate object of this invention is to provide a machine for accurately and readily setting rivets and burs on garments, and other articles where needed, and where and when it is desirable to present a neat and symmetrical appearance of the riveted or upset end of the rivet; but the invention in principle is applicable to riveting or setting machines generally.

The invention consists of a riveting machine having a raceway intercepted by a setting plunger so that the bur or female member will be definitely delivered to the holder in setting position, and a stationary anvil or die onto which the rivet or male member is delivered and by which it is presented to the setting plunger in a releasable way, and a reciprocating finger for moving the male member from its point of delivery to the anvil, as I will proceed now to explain and finally claim.

In the accompanying drawings illustrating the invention, in the several figures of which like parts are similarly designated, Figure 1 is a side elevation of the machine with the parts in position when the bur is about to be delivered to the holder, the stand or post being broken out between its foot and upper end. Fig. 2 is a front elevation of the upper part of the machine. Fig. 3 is a fragmentary sectional elevation of the plunger, holder and die with female and male members in position ready to be set. Fig. 4 is a front elevation, on a larger scale, of the anvil members. Fig. 5 is a perspective view of one of the yielding cheek-pieces or jaws of the anvil, looking at its inner side. Fig. 6 is a sectional elevation of the upper part of the machine showing its extremes of movement by full and dotted lines, respectively. Fig. 7 is a perspective view of the anvil members shown in Fig. 4, with the cheek-piece or jaw in the foreground detached. Fig. 8 shows in top plan and cross-section the female member or bur. Fig. 9 shows in inverted plan and partial longitudinal section the male member or

rivet, in the instance shown, a tack. Fig. 10 shows the male and female members set or riveted upon two thicknesses of material. Fig. 11 shows the obverse of the joint of the push-finger, on a larger scale. 60

As already stated, the invention in principle is applicable for riveting generally for setting buttons by means of metallic fastenings, such as tacks or rivets, and for other purposes, but the invention will be better 65 understood by explaining it as embodied in a machine for setting rivets and burs such as illustrated in Figs. 8 to 10 of the accompanying drawings, and this I will proceed now to do, with the understanding that the 70 invention is not limited to the particular use or machine shown.

A stand or post 1 supports a table 2 on which rises a suitable head 3 to take certain moving and other parts of the machine. 75

4 is a bracket in which the main shaft 5 is mounted, and 6 is a band pulley thereon by which power may be applied. Any suitable stopping and starting mechanism may be used for effecting the co-operation of the 80 pulley and shaft, it being here noted that an intermittent rotary motion is used for operating the setting elements of the machine when the rivets are to be set at irregular intervals or at such points as require 85 careful adjustment of the article to be riveted in order to secure the proper location of the rivets, as on the pockets, flies and other parts of overalls. The treadle 7 may be connected by rod 8 with the crank arm 90 9 of the stopping and starting mechanism, so as to put it in control of the operator.

The head 3 has a bracket 10 which supports the bur hopper 11, and another bracket 12 which supports the tack or rivet hopper 95 13, and these hoppers are provided with chutes or raceways 14 and 15, respectively, which lead to the setting plunger 16 and the anvil 17, respectively.

The plunger 16 is arranged vertically in 100 the head and is jointed to a lever 18 pivoted at 19 on the head and connected by a connecting rod 20 with a crank-arm 21, or other suitable means on the shaft 5. This connecting rod may be and preferably is of the 105 shock-absorbing type illustrated in my Patent No. 1,134,973, dated April 6, 1915.

The plunger 16 has its die end 22 made with a cavity 23 shaped to receive the socket portion 24 of the bur 25 and to center the bur 110

over the tack 26, and this cavity also has a 5 teat 27 to enter the depression 28 in the bur's socket, so that in the setting or riveting of the article the bur is held by the die end of the plunger both on its flange and its socket and its deformation prevented in the act of setting or riveting, and the tack point meets a solid resistance member which compels its upsetting or clenching within the socket of 10 the bur. Furthermore, the contour of the depressed socket simulates the riveting where no protecting cap is used, but in a symmetrical and pleasing or attractive finish. The burs are delivered edgewise one at a time 15 from the raceway 14 to the plunger while the plunger is in the setting position, and are arrested by the plunger until the plunger has returned and then a bur is dropped into the bur-holder in position to be acted upon 20 by the plunger upon its next descent or setting movement. This bur-holder is composed of a pair of laterally-separable fingers 29 pivotally connected at 30, and having their adjacent sides recessed to conjointly form a 25 slot 31 in which are screws 32 backed by washers 33 which screws are threaded into the face of the head so as to secure the holder to the head in a longitudinally sliding relation and yet permit of the lateral separation 30 of the fingers to discharge the bur. The fingers are held closed by any suitable resilient means, such as a spring 34 fastened to the fingers near their pivotal points, as by clips 35, and having their opposite ends bent into 35 holes in the outer edges of the fingers near their lower ends. The holder is hung to the pivot 36, Fig. 1, which connects the lever 18 with the plunger 16, by means of hooks 37, so as to insure a positive return or upward 40 movement of the holder. The tips 38 of the fingers extend backwardly beneath and in line with the plunger, and these tips are recessed at 39, Figs. 3 and 6, to receive the bur, flange down, and locate it directly beneath 45 the plunger with its cap or socket in line with the die cavity in the end of the plunger, so that as the plunger descends to set or rivet the article, the bur socket will enter the die cavity in the plunger and the holder will be 50 carried down with the descending plunger partly by gravity and partly by the contact of the plunger, and finally reaching its limit of movement determined by the engagement of the upper end of the slot 31 with the up- 55 permost screw 32, the plunger in its further descent will part or separate the constituent fingers laterally and carry the bur down with it to the tack or rivet.

The anvil 17 comprises a block 40 mounted 60 upon the table and having converging sides 41 at its front and a raceway 42 at its rear into which opens the tack raceway or chute 65 transversely. The anvil has a seat 43 of a shape corresponding to the shape of the head of the tack or rivet. To the inclined 70 sides are yieldingly fitted the cheek-pieces or jaws 44, normally projected above the level of the anvil, as by springs 45, and capable of moving downwardly. These cheek-pieces are secured to the anvil not only in 75 such way as to permit this downward yielding movement, but also to have a laterally yielding movement, and these two movements may be obtained by the use of the slots 46, screws 47 and springs 48, in addition to the 80 springs 45. The cheek-pieces yield downwardly under pressure of the plunger so as to permit the bur and tack or rivet to meet in close contact on opposite sides of the article being riveted, and to ultimately release the tack head from the cheek-pieces, and they yield laterally to insure a spring 85 engagement of the tack head and release it when set. The inside of each cheek-piece is provided with a horizontally arranged tapering groove 49 alined with the raceway 42 and running out to nothing forward, so as to hold the tack or rivet by its head until set. The downward movement of the cheek-pieces and their lateral yield insure the release of the 90 tack-head from these grooves when the riveting is completed. The springs 45 may be of wire, held to the anvil by screws 50, one of their ends resting on the base of the anvil and their other ends engaging pins 51 on the 95 cheek-pieces.

The raceway 42 and the cheek-pieces combine to guide the tack or rivet from the hopper raceway to the point of application, and the tack or rivet is positively moved into 100 position by a push-finger 52, having its forward end 53 flat and inclined, upward and rearwardly and its tip beveled and crossing the raceway. Said finger slides back and forth over the raceway from just behind the 105 hopper raceway 15 to a point forward sufficiently far to insure the location of the tack or rivet in the seat 43, where it is held by the cheek-pieces closing in yieldingly upon it until the plunger descends in the act 110 of setting or riveting as previously described. This push-finger is yieldingly pivoted at its rear end to an arm 54 which is pivotally suspended from a pin 55 mounted in a bracket 56 fixed to the head 3, and this 115 arm is held up by a spring 57 stretched between it and the head so as normally to throw the push-finger forward while the yielding connection of the push-finger with said arm tends to hold the forward end of the push-finger in contact with the anvil. This yielding connection may be a coiled or other spring 58 mounted upon the pin joining the push-finger and arm and having its 120 opposite ends engaging the push-finger and arm, as shown in Fig. 11. The arm is engaged by a pin or roller 59 on one limb of a bell-crank lever 60 also pivoted on the pin 55, the other limb of this bell-crank lever 125 engaging a slot in a link 61 hung from the 130

lever 18, so that the push-finger is automatically retracted as the lever 18 is raised to depress the plunger, and a loose motion is provided to permit the push finger to move forward under the combined action of the descending lever 18 and the spring 57.

The raceway 42 is provided with a cam surface 62 rising above its level from a point in advance of the raceway 15 where it enters the raceway 42 and extending to the rear of it. The cam surface serves to lift the push finger over the raceway 15 where it joints raceway 42 and permits its inclined leading end to ride safely over the point without jamming the tack or rivet in the raceway, and to engage such point in its forward movement sufficiently to move the tack or rivet beyond the cam surface and then drop behind it and push it into position on the anvil and into engagement with the spring cheek-pieces by which it is held to be set. There is enough play in the raceway 42 for the head of the tack or rivet to permit the latter to tilt under the receding push-finger.

The bur hopper 11 is here shown as given an intermittent rotary motion to feed the burs to the raceway 14, by a pawl and ratchet mechanism 63 actuated by a rod 64 connected with a pawl carrier 65 at one end and a bell-crank lever 66 at the other end; the pawl carrier being mounted on the hopper shaft and the bell-crank lever pivoted on the bracket 10 and having a forked end 67 engaging a pin 68 on the lever 18. The pawl carrier is also connected by the rod 69 with the cut-off or gate 70 on the raceway 14 and operates it to discharge one bur at a time. The tack or rivet hopper 13 is given an intermittent rotary motion, by means of a pawl and ratchet mechanism 71 having a pawl carrier 72 loose on the shaft of the hopper and connected by rod 73 with the bell-crank lever 60. This pawl carrier has a rod 74 which is connected with the cut-off or gate 75 on the tack or rivet raceway 15 to operate it to release the tacks or rivets one at a time.

The operation is as follows: Assuming that the machine is to be used for riveting or setting rivets or tacks and burs of the character illustrated in Figs. 8, 9 and 10, wherein the bur instead of being of annular form as usual, has a cap or socket made with or applied to it, so as to receive and conceal the upset or clenched or riveted end of the fastening, and such fastening is a tack, and that these devices are to be used for staying the meeting edges of parts of garments, such as the pockets, flies, and other parts of overalls, then such burs are placed in the hopper 11 and fed to the raceway 14 by the intermittent rotation of the hopper and from the raceway delivered one by one by its cut-off or gate 70 to the plunger 16 and then the holder. Tacks are placed in the hopper 13

and by its intermittent rotation fed to the raceway 15 and by its cut-off or gate 75 delivered one by one to the anvil 40 on which they are positioned beneath the plunger and bur by the coöperation of the push-finger 52 and the cheek-pieces 44. The garment to be riveted is held between the bur-holder and cheek-pieces, and then the plunger descends and carries the bur with it and out of the holder, depressing the cheek-pieces and forcing the tack through the garment into the bur and clenching it within the cap or socket of the bur, the bur meanwhile being supported within and by the die end of the plunger, and the finished riveting presenting a smooth, symmetrical appearance, simulating more or less closely, the best machine riveting. Should the bur fall into the holder askew, as indicated in Fig. 3, it will be righted by the plunger. The push-finger moves a tack into setting position and remains in this position while the plunger and holder are descending and until the tack is about to enter or has entered the garment, and thus its flat forward end may be utilized as a support for the garment during the first part of the setting operation. Just before the riveting is effected, the push-finger recedes, the plunger and holder complete the operation of riveting and then rise, and the push-finger again moves forward and places another tack in position for another riveting operation. As shown in Figs. 2 and 6 the head is arched at its bottom and through this arch the push-finger plays. Any suitable means may be used to limit the forward movement of the push-finger, such as the rear wall of the arch, as indicated in Fig. 6.

What I claim is:—

1. A machine for setting or riveting male and female members of a fastening device, having a setting anvil including a raceway, a setting plunger, means to deliver the female members one by one to the plunger, and means to deliver the male members one by one to the setting anvil including a push-finger suspended over the raceway and having sliding contact with the upper surface thereof, and means to impart longitudinal reciprocation to said push-finger for positioning the male member beneath the female member.

2. A machine for setting or riveting male and female members of a fastening device, having a setting anvil including a raceway, a setting plunger, means to deliver the female members one by one to the plunger, means to deliver the male members one by one to the setting anvil including a push-finger suspended over the raceway, means to yieldingly press said push-finger into sliding contact with the upper surface of the raceway, and means to impart longitudinal reciprocation to said push-finger for posi-

tioning the male member beneath the plunger.

3. A machine for setting or riveting male and female members of a fastening device, having a setting anvil including a raceway, a setting plunger, means to deliver the female members one by one to the plunger, means to reciprocate the plunger, means to deliver the male members one by one to the setting anvil including a push-finger yieldingly suspended above the raceway and in contact with the upper surface thereof, means to impel said push-finger forwardly in the direction of its length, and means including a slotted link connecting said push-finger with the means for reciprocating the plunger to retract said push-finger.

4. A machine for setting or riveting male and female members of a fastening device, having a setting anvil including a raceway, a setting plunger, means to deliver the female members one by one to the plunger, means to deliver the male members one by one to said anvil including a push-finger, an arm pivotally suspended above said push-finger and to which said push-finger is pivoted, means to impel said push-finger and arm forward, means to move said push-finger and arm in the opposite direction, and means applied to the push-finger to permit it to yield vertically.

5. A machine for setting or riveting male and female members of a fastening device, having a setting anvil and a setting plunger, means to deliver the female members one by one to the plunger, means to deliver the male members one by one to said anvil including a longitudinally reciprocating push-finger for positioning the male members beneath the plunger, a pivoted arm on which the push-finger is pivoted, a bell-crank co-operating with said arm to move it in one direction, a spring to move said arm and bell-crank in the opposite direction, and a lever connected with said bell-crank and with the plunger for effecting the coaction of the plunger and anvil in riveting the male and female members on an article.

6. In a riveting machine, an anvil having upwardly converging sides, cheek-pieces having slots, fastening means passed through said slots and engaging the sides of the anvil to secure the cheek-pieces to the sides of the anvil convergently and movably, and resilient means applied to the cheek-pieces to permit movement of said cheek-pieces in the direction of their convergence and also transversely thereto and compel their restoration to normal position.

7. In a riveting machine, an anvil having upwardly converging sides, cheek-pieces having slots, screws passed through said slots and engaging said anvil to secure the cheek-pieces thereto and adapt them for movement laterally and vertically with rela-

tion to the anvil, resilient means interposed between said screws and cheek-pieces to permit of the lateral movement of said cheek-pieces, and resilient means applied to said cheek-pieces to permit of their vertical movement, said resilient means adapted to return said cheek-pieces to normal position. 70

8. In a riveting machine, an anvil having upwardly converging sides, cheek-pieces provided with slots, screws passing through said slots and engaging said anvil to apply the cheek-pieces thereto so that they may move thereon laterally and vertically, and springs interposed between said screws and cheek-pieces and between said cheek-pieces and anvil to permit of said lateral and vertical movements respectively and return said cheek-pieces to normal position. 75

9. In a riveting machine, an anvil for positioning and supporting the rivet while being set, cheek-pieces convergently arranged upon the sides of said anvil and movable in the direction of their convergence and transversely thereto, and separate springs for independently counteracting such movements. 80

10. In a riveting machine, an anvil for positioning and supporting the rivet while being set and having upwardly converging sides, cheek-pieces convergently arranged upon the sides of said anvil and movable thereon in the direction of their convergence and also transversely toward and from the anvil, and resilient means reacting upon the cheek-pieces and the anvil to compel movement of said cheek-pieces in the direction of their convergence, and resilient means connected to the anvil and acting upon the cheek-pieces to permit transverse movement of the cheek-pieces relatively to the anvil, both of said resilient means also serving to compel restoration of the cheek-pieces to normal position. 95 100

11. In a riveting machine, an anvil, means to deliver a rivet thereto, and vertically and laterally yielding cheek-pieces applied to said anvil to hold the rivet, said cheek-pieces having inside tapering grooves near their upper edges to engage the head of the rivet. 110 115

12. In a riveting machine, an anvil, means to deliver a rivet thereto, and vertically and laterally yielding cheek-pieces applied to said anvil to hold the rivet, said cheek-pieces having grooves near their upper edges to engage the head of the rivet, said grooves running out to nothing forward. 120

13. In a riveting machine, the combination of a plunger, a holder co-operating therewith to present the female member of a fastener to the male member, means to reciprocate said plunger, an anvil adapted to hold the male member of such fastener in position to engage the female member, a push finger to place said male member in 125 130

such position, and means to actuate said push-finger connected with the plunger operating means and timed to cause the push-finger to hold the male member in position to be riveted and to support the article to be riveted and then recede and engage another male member to forward it to the anvil.

14. In a riveting machine, the combination of a plunger, a holder coöoperating therewith to present the female member of a fastener to the male member, means to reciprocate said plunger, an anvil adapted to hold the male member of such fastener in position to engage the female member, a push-finger to place said male member in such position, means to actuate said push-finger connected with the plunger operating means and timed to cause the push-finger to hold the male member in position to be riveted and to support the article to be riveted and then recede and engage another male member to forward it to the anvil, and means to compel the push-finger to harmlessly ride over any obstructions standing in its path of movement and to push forward any male members in the path of its forward movement.

15. A machine for setting or riveting male and female members of a fastening device, having a setting anvil and a setting plunger, means to deliver the male and female members one by one respectively to the setting anvil and plunger, and a longitudinally reciprocating push-finger for positioning the male member beneath the female member, the leading end of said push-finger extending across the anvil and having a flat upper

surface serving as a temporary rest for the article to be riveted.

16. A machine for setting or riveting male and female members of a fastening device, having a setting anvil and a setting plunger, and means to deliver the male and female members one by one respectively to the setting anvil and plunger, the means for delivering the male member including a longitudinally reciprocating push-finger for positioning the male member beneath the female member, the leading end of said push-finger extending across the anvil and having a flat upper surface upwardly inclined toward the rear and serving as a temporary rest for the article to be riveted.

17. A machine for setting or riveting male and female members of a fastening device, having a setting anvil and a setting plunger, and means to deliver the male and female members one by one respectively to the setting anvil and plunger, the means for delivering the male member including a longitudinally reciprocating push-finger for positioning the male member beneath the female member, the leading end of said push-finger extending across the anvil and having a flat upper surface upwardly inclined toward the rear and serving as a temporary rest for the article to be riveted and having a beveled tip to engage the male member.

In testimony whereof I have hereunto set my hand this 12th day of June, A. D. 1915.

FREDERICK E. STANLEY.

Witnesses:

C. P. COOK,
JOHN B. KENDRICK.

It is hereby certified that in Letters Patent No. 1,182,594, granted May 9, 1916, upon the application of Frederick E. Stanley, of Waterbury, Connecticut, for an improvement in "Riveting-Machines," an error appears in the printed specification requiring correction as follows: Page 4, line 118 and lines 119-120, claim 12, for the compound word "check-pieces" read *cheek-pieces*; and that the said Letters Patent should be read with this correction therein that the same may conform to the record of the case in the Patent Office.

Signed and sealed this 23d day of May, A. D., 1916.

[SEAL.]

J. T. NEWTON,

Acting Commissioner of Patents.
